UNITED STATES PATENT OFFICE.

HUGH C. ROSS, OF TOLEDO, AND HARRY W. FALCONER, OF NEAR FERRYSBURG, OHIO;
SAID ROSS ASSIGNOR TO SAID FALCONER.

IDENTIFICATION DEVICE FOR VEHICLES.

Application filed April 8, 1926. Serial No. 100,492.

This invention relates to identification devices for vehicles and has for its object the provision of a simple and efficient device of this character which is adapted to be readily secured to a part of the vehicle and when in place, is practically impossible to remove without cutting or mutilating the associated parts. Further objects and advantages will hereinafter appear.

For purposes of illustration the invention is shown in the accompanying drawing, in which:

Fig. 1 is a front elevation of the identification device secured to a vehicle part; Figure 2 is a top plan view partly in section of the device in assembled relation; Figure 3 is a transverse sectional view on the line 3—3 of Fig. 1; and Fig. 4 is a fragmentary longitudinal sectional view of the device and 20 casing.

The illustrated embodiment of the invention comprises a vehicle part 1 and this may be the instrument board, the engine casing, or any other part. Secured to the part 1 is a metal casing 2 which may be rectangular in form and may be provided with a flange 3 extending therearound. The flange 3 may be rigidly secured to the vehicle part 1 in any suitable manner as by spot welding. Formed in the vehicle part 1 is a rectangular opening 4 registering with an opening 5 in the casing 2, the other sides of the casing being closed.

Disposed within the casing 2 and visible thru the registering openings 4 and 5 is an identification device bearing the serial number or license number of the vehicle and this device may consist of a plurality of metal blocks 7 having dove tails 7 on one side fitting into recesses 8 in adjacent blocks. End blocks 9 and 10 are provided and these are formed with one flattened surface to abut against the end of the casing, the block 9 being formed with a dove tail and the block 10 with a recess for engaging adjacent blocks. As shown in Fig. 1 the blocks 6 may have number or letters engraved, embossed or otherwise suitably formed thereon, although the design of the identifying 50 matter on the blocks forms no part of this invention.

For holding the blocks in assembled relation each block is formed with an opening or passage 11 having enlarged portions 12 at opposite ends and adapted to register

with adjacent openings or passages in adjacent blocks. Extending through the registering passages is a twisted wire 13 having oppositely tapered end portions 14 terminating slightly short of the end of the 60 passage in the end blocks 9 and 10. For securely holding the blocks together in assembled relation and to provide a unitary arrangement cementitious material 15 is poured into the registering passages 11 and 65 enlarged portions 12, entirely surrounding the twisted wire 13 and tapered end portions 14. It will thus be seen that separation of the blocks from each other either longitudinally or transversely is rendered 70 practically impossible.

An outstanding characteristic of this invention resides in the provision of means for automatically locking the assembled blocks in the casing 2 when the block assembly is 75 inserted into the casing. For this purpose the opposite sides of the blocks are formed with grooves 15, which are adapted to register with grooves 16 in the casing 2 when the block assembly is inserted into the casing. Disposed in the registering grooves 15 and 16 are bowed leaf springs 17, and in this instance four springs are employed, 80 two at each end of the block assembly.

In practice the springs 17 are first placed 85 in the grooves 15 with the bow portion of the springs extending outwardly from the block assembly. By depressing the bow portions of these springs so as to lie flat in the grooves, it will be readily seen that the 90 block assembly may be inserted into the casing 2 through the opening 4 in the vehicle part 1. After the block assembly has been inserted a sufficient distance into the casing the springs 17 automatically expand into 95 the groove 16 in the casing 2. By this means the blocks are held securely in place in the casing, and cannot be removed therefrom. It will also be seen that the sides of the 100 grooves 16 in the casing provide abutments against which the bow portion of the leaf spring 17 may engage so as to prevent relative movement between the block assembly and the casing.

It is to be understood that other means 105 may be utilized for holding the block assembly in place and we do not desire to be limited to the use of leaf springs which are loosely disposed in the grooves. For example, a spring may be utilized which is fixed 110

at one end and may permit the block assembly to be inserted into the casing, but will prevent removal thereof. It is also to be understood that although we have shown and described a construction which is the best form known to us at the present time, the above is given by way of illustration and not of limitation, and numerous changes in details of construction and arrangement may 10 be effected without departing from the spirit of the invention, especially as defined in the appended claim.

What we claim as new and desire to secure by Letters Patent is:

15 An identification device for vehicles comprising in combination with a vehicle part, a casing fixed to said part and having an

opening, a plurality of identification blocks in said casing visible through said opening, said casing having opposed recesses and said blocks having opposed grooves registering with said recesses, leaf springs loosely disposed in said registering grooves and recesses for preventing removal of said blocks from the casing, and means for securing said blocks in assembled relation, said means comprising a twisted wire extending through said blocks and cementitious material surrounding said wire.

In testimony whereof we have hereunto signed our names to this specification.

HUGH C. ROSS.
HARRY W. FALCONER.
